(57) **CLAIM**

The ornamental design for a chair, as shown and described.

DESCRIPTION

FIG. 1 is a perspective view of the chair;

FIG. 2 is a front elevational view of the chair;

FIG. 3 is a rear elevational view of the chair;

FIG. 4 is a left side elevational view of the chair;

FIG. 5 is a right side elevational view of the chair;

FIG. 6 is a top plan view of the chair; and,

FIG. 7 is a bottom plan view of the chair.

The broken lines immediately adjacent to solid lines illustrate claimed stitching. All other broken lines illustrate portions of the chair that form no part of the claimed design.

1 Claim, 7 Drawing Sheets
